UNITED STATES PATENT OFFICE.

NORMAN A. ROBERTSON, OF NEW YORK, N. Y.

APPARATUS FOR BENDING AND DRAWING SHEET METAL.

1,078,959.

Specification of Letters Patent.

Patented Nov. 18, 1913.

Original application filed May 8, 1912, Serial No. 695,881. Divided and this application filed September 23, 1912. Serial No. 721,957.

To all whom it may concern:

Be it known that I, NORMAN A. ROBERTSON, a citizen of the United States, residing in the borough of Brooklyn, county of Kings, city and State of New York, have invented certain new and useful Improvements in Apparatus for Bending and Drawing Sheet Metal, of which the following is a specification.

10 This application is a division of my application No. 695,881, filed May 8, 1912, describing a method and apparatus for bending and drawing sheet metal, such for example as iron or steel or aluminum, and 15 especially for drawing the irregularly-shaped parts of the bodies of automobiles and similar vehicles; the present application being limited to the apparatus.

Automobile bodies usually comprise a supporting floor, and sides and ends which 20 inclose the seats. The sides and ends have been made of plates of metal some or all of which are bent both in a longitudinal and in a transverse direction so as to produce 25 convenient and graceful shapes. Except at the corners between the sides and the ends the curvature of the plates has been comparatively slight, and it has been the practice heretofore to shape the plates by 30 hand, at a very considerable expense. This invention provides for the drawing of the plates into the desired shape entirely by machinery, thus securing greater accuracy and economy than can be secured by hand 35 work.

In the accompanying drawings,—Figures 1, 2 and 3 are respectively an elevation, inverted plan, and section (on the line 3—3 of Fig. 1) of a plate adapted to form the 40 rear end of an automobile body; Figs. 4, 5, 6 and 7 illustrate a suitable embodiment of this invention for making the end plate of Figs. 1, 2 and 3; Fig. 4 being a front elevation, partly in section, Fig. 5 being 45 a horizontal section on the line 5—5 of Fig. 4, Fig. 6 a central transverse section, and Fig. 7 an end elevation.

The article shown in Figs. 1, 2 and 3 is an unfinished end plate or seat back and is 50 selected as typical of the numerous different shapes which can be made according to the principles of this invention. Calling the distance from right to left in the drawing the length of the sheet, Fig. 2 shows that it is 55 curved longitudinally to form the center A

and the end portions B at approximately a right angle to the central portion; and Fig. 3 shows that the central portion is curved transversely, the curve being of slight degree and being of reversed or S-shape. Adjacent to the upper and lower edges of the plates are stiffening ribs C and D stamped therein. Similar intermediate ribs F are formed in the back or central portion. The ends of the plate are unfinished, being subsequently 60 trimmed and bent in any usual or suitable press. In shaping the plate, the blank is held at two opposite sides, and left free at the other two sides. For example, for making the plate of Fig. 1 it would be 65 held only at the end portions B. Notwithstanding that the blank is free at the top and bottom sides, it is drawn into a shape which is curved in the transverse direction as well as in the longitudinal direction, the 70 holding of the ends being sufficient to permit the limited amount of transverse shaping required. It is possible in fact to secure most of the shapes desired by the mere pressure of the shaping punch upon one face 75 of the sheet, without the necessity of an opposing die, the desired shape being obtained by the mere stretching of the metal over the punch by reason of the relative movement between the punch and the 80 clamped ends of the blank.

In the machine illustrated a pair of blank holders or grippers G are located at each side of the machine, being removably mounted on blocks H which are mounted, one at 85 each side of the machine, on the upper ends of a pair of plungers H' which work in hydraulic cylinders J; the blocks H at opposite sides being connected to each other by means of cross bars K, and the cylinders 90 J being mounted on a cross-head or platen L on the top of the plunger M of the main ram by which the punch N is raised and lowered. The upper die O is fixed in the upper press head O' and carries removable 95 grippers P. The upper grippers P and the lower grippers G are made detachable, so that grippers of different shapes may be put into the machine for making plates having differently shaped ends.

100 The cylinders J are connected to any usual or suitable type of accumulators whereby a constant hydraulic pressure is maintained on the plungers H, this pressure being calculated to permit a drawing of the 105 110

sheet Q through the grippers with considerable friction as the punch advances, and being adjustable to different pressures. The punch N is mounted on a frame R which is 5 provided with projecting lugs S which engage the upper edges of the tie bars K so as to hold the grippers G away from the blank until the punch commences to advance; after 10 which the blank is gripped with a constant pressure during the entire drawing operation, the lugs S rising clear above the tie bars K. The punch N and die O are removable like the grippers P and G to adapt the machine for bending plates of different 15 shapes. The attachment of the cylinders J to the ram makes a perfectly simple and very strong construction which works automatically to first clamp the blank and then draw it while holding its ends with a 20 substantially constant pressure sufficiently moderated to prevent tearing the blank. The grippers G are inclined on their ends and there is consequently a strong lateral force 25 acting against the grippers and the blocks H. But these blocks bear inward against the punch N and are thereby absolutely held against yielding. The ends of the blank 30 may be quite long and weighty and the faces of the grippers G and P are inclined to give a substantial downward incline to the gripped ends of the blank, thus minimizing the difficulty of drawing them through the grippers.

The blank Q being placed in the machine, 35 its ends are gripped with a determined pressure at the first upward movement of the punch. During the further movement of the punch the ends, though permitted to slip as far as necessary, are held with considerable 40 firmness, so that they first draw the comparatively thin metal closely over the punch and make it fit the punch, somewhat in the manner in which a new glove is drawn over one's hand, and thereafter permit the ends 45 to slide through the grippers as the punch advances. I prefer to provide ribs T on the punch and corresponding grooves U on the die, for forming the stiffening ribs in the plate; because the ribs T on the punch 50 appear in practice to give the punch a better grip on the sheet even before the latter is pressed clear up to the die. To secure the general curves desired it is not necessary to press the sheet clear against the die, the 55 drawing of it over the punch alone being sufficient with some shapes and metals. In other cases it may be made to bear against the die where the shape desired is difficult to secure otherwise. Or, as in the case illustrated, the punch may be made to carry the 60 blank against the die throughout the entire area of the blank, and such contact is necessary to form the sharply curved stiffening ribs of the plate shown in Figs. 1, 2 and 3.

After the drawing operation in the machine 65 illustrated, the ends of the blank may be trimmed and further bent, drawn, or stamped as desired. For example, end extensions B' and end ribs C' D' and E may be formed as shown, in dotted lines, in Figs. 70 2 and 3.

Though I have described with great particularity of detail a specific machine embodying this invention, yet it is not to be understood therefrom that the invention is 75 restricted to the particular machine described. Various modifications thereof in detail and in the arrangement and combination of the parts may be made, and segregable parts of the apparatus may be used in 80 other connections, by those skilled in the art, without departure from the invention.

What I claim is:—

1. An apparatus for bending and drawing sheet metal to make parts of vehicle bodies 85 or the like, which are curved in two planes transverse to each other, comprising grippers adapted to hold two opposite sides of the blank and to leave it free at the other two sides, a punch located between said grippers, said punch having its face curved both in planes parallel to the sides which are held and in planes perpendicular thereto, and a die against which the intermediate part of the blank may be pressed by said punch, said 95 die and punch being also formed with registering ribs and grooves respectively to form stiffening ribs on the blank.

2. An apparatus for bending and drawing sheet metal to make parts of vehicle bodies 100 or the like, comprising an upper pair of grippers P and a lower pair of grippers G, said grippers adapted to hold two opposite sides of the blank and having their faces inclined downward toward the outer side so as to provide for a downward incline of the extending ends of the blank, and means for bending and drawing the portion of the blank between the grippers at opposite sides. 105

3. An apparatus for bending and drawing sheet metal, comprising grippers, a punch, and hydraulic devices carried by said punch for pressing and holding said grippers into engagement with the work as the punch is advanced, said punch being adapted to engage and withdraw said grippers near the end of its retractile movement. 110

4. An apparatus for bending and drawing sheet metal, comprising grippers G adapted to engage and bear against the work on an angle tending to press said grippers inward, and a punch located between said grippers in position to resist the inward thrust thereof. 120

5. An apparatus for bending and drawing sheet metal, comprising grippers adapted to 125 yieldingly hold two opposite sides of the blank while leaving it free at the other two sides, and a punch located between said gripp-

pers, said punch having its face curved both in planes parallel to the sides which are gripped and in planes perpendicular thereto, and movable relatively to the grippers to a final position projecting beyond them, the grippers adapted to hold the blank with sufficient force to draw the sheet metal into conformity with the curved face of the punch while permitting the blank to feed between the gripping surfaces as it is drawn by the punch, such feed being unequal at different points along the gripped sides of the blank.

6. An apparatus for bending and drawing sheet metal, comprising grippers adapted to hold two opposite sides of the blank and to leave it free at the other two sides, a punch located between said grippers, said punch having its face curved both in planes parallel to the sides which are held and in planes perpendicular thereto and movable relatively to the grippers to a final position beyond them, whereby in said position the distance from one gripper to the other following the face of the punch varies in different planes transverse to the grippers, and the grippers adapted to hold the blank yieldingly and firmly enough to draw the metal against the contour of the punch during such advance movement while permitting the metal to feed between the gripping faces, such feed being

unequal at different points along the grippers.

7. An apparatus for bending and drawing sheet metal, comprising grippers adapted to yieldingly hold two opposite sides of the blank while leaving it free at the other two sides, and a punch located between said grippers, said punch having its face curved both in planes parallel to the sides which are gripped and in planes perpendicular thereto and movable relatively to the grippers to a final position projecting beyond them, the grippers adapted to hold the blank with sufficient force to draw the sheet metal into conformity with the curved face of the punch while permitting the blank to feed between the gripping surfaces as it is drawn by the punch, such feed being unequal at different points along the gripped sides of the blank, and a die located adjacent to the final position of the punch and conforming thereto, whereby the already conformed blank is finally squeezed between the punch and die.

In witness whereof, I have hereunto signed my name in the presence of two subscribing witnesses.
